MEANS FOR MAKING PACKING MATERIAL
FOR CHEMICAL APPARATUSGeorge B. Bailey and Otto Ziegler, Michigan City,
Ind., assignors to The Hays Corporation, Michigan
City, Ind., a corporation of Indiana

Application May 24, 1945, Serial No. 595,526

11 Claims. (Cl. 140—105)

1

This invention relates to means for making packing material for a chemical apparatus. More particularly, the invention relates to means for bending, shaping and cutting wire to form packing material for use in gas analyzers, reflux condensers, gas scrubbers, and like chemical apparatus.

Packing material of this character is described in the patent application of George B. Bailey, Serial No. 577,851, filed February 14, 1945. It is made up of a large quantity of similar small wires which are so bent and twisted that they are close spaced when filling a chamber of a chemical apparatus and present a large surface area to facilitate chemical reaction in the apparatus, without so packing or otherwise compacting as to obstruct fluid flow in the chamber. The wires are preferably bent in sinuous shape and are also twisted along their length in such a manner that each will contact a flat surface at only a few spaced points thereof. The wires should be of the same shape and the same length to insure uniformity of the packing throughout the space or chamber receiving the same.

It is the primary object of this invention to provide apparatus for making packing material of the type above mentioned.

A further object is to provide a simple, accurate and compact device for producing packing material rapidly and uniformly.

Other objects will be apparent from the description, drawing and appended claims.

In the drawing:

Fig. 1 is a top plan view of the device, with part of the gear block removed.

Fig. 2 is a longitudinal vertical sectional view taken on line 2—2 of Fig. 1.

Fig. 3 is an enlarged side view of an element of the packing.

Fig. 4 is an edge view of a packing element taken at right angles to Fig. 3.

Referring to the drawing, the numeral 10 designates a base plate. Standards 11 project upwardly from opposite sides of the base plate at one end thereof and mount a transverse shaft 12. The shaft 12 journals a plurality of wire reels 13. Spacers 14 preferably separate the adjacent reels and position them properly along the shaft. Shaft 12 may be slideable endwise relative to the mounting standards or may be otherwise removably mounted on the standards to permit ready replacement of the reels.

A second pair of standards 15 adjacent to standards 11 serves to journal a lower transverse shaft 16 and an upper transverse shaft 17. Shaft 16

2

mounts a plurality of spaced crimping gears 18 and shaft 17 mounts a plurality of spaced crimping gears 19 meshing with gears 18. The crimping gears have teeth of rounded contour which are so shaped and proportioned as to provide clearance for wire 20 fed from reels 13 and passing therebetween to be crimped in sinuous form as shown in Fig. 2. Spacers 21 serve to position the gears 18 and 19 properly upon their respective shafts.

A lower gear block 22 extends transversely of the base plate in spaced relation to standards 15, and an upper gear block 23 is removably mounted thereon. The block 22 has a plurality of longitudinal passages 24 formed therein, each in longitudinal alignment with one set of meshing gears. These passages have enlarged mouths in which bushings 25 are mounted. Bushings 25 preferably have enlarged heads 26 bearing against the front edge of the block and shank portions which are slotted vertically. The head 26 has a vertically elongated passage communicating with the shank slot and of a size to freely and slidably receive the wire crimped by gears 18—19. The passage 24 in the gear block 22 communicates with circular recesses 27 formed in said block to receive a plurality of sets of crimping gears 28, 29, 30 and 31 positioned horizontally. The gears of each of these sets have rounded teeth which mesh but have sufficient clearance therebetween to accommodate the passage of one of the wires 20 therebetween. The horizontal crimping gear sets are arranged in staggered relation, as shown in Fig. 1. The innermost gears of the outer sets preferably mesh directly with the outermost gears of the adjacent inner sets, so that there is a direct drawing connection for each pair of gear sets. One of the directly meshing gears of each such pair of sets has a stud shaft 32 journaled in the upper gear block 23 and mounts a bevel gear 33 at its upper end. The block 22 has longitudinal grooves 34 aligned with grooves 24 leading from the gear recesses 27 to the rear thereof. Grooves 34 accommodate the lateral crimping of the wires 20 by the gears in the gear blocks, and each is longitudinally inclined upwardly and outwardly, as shown in Fig. 2, from a level approximately flush with the bottom of the gear at its inner end. The lower block 22 projects beyond the upper block 23 at its rear end, and mounts a hardened shear plate 35 whose upper surface is flush with the bottoms of the outer ends of the grooves 34 in the lower block.

One or more standards 36 project upwardly from each side of plate 10 at the rear thereof.

These standards journal a cutter shaft 37 which mounts a plurality of discs 38 in spaced relation and longitudinally aligned with grooves 34. Each disc mounts a plurality of equiangularly arranged projecting radial blades 39 whose outer edges cooperate with the shear plate 35 to cut wire projecting beyond said plate.

One end of shaft 37 mounts a drive pulley 40 for connection with a power or drive member by means of a belt (not shown). The opposite end of shaft 37 mounts a pinion 41. A stud shaft 42 is journaled in the standard 36 adjacent to pinion 41, and mounts a gear 43 which meshes with pinion 41. Shaft 42 also mounts a pinion 44. A transverse shaft 45 is journaled in opposite standards 36 in spaced relation above the gear blocks and above the bevel gears 33, and mounts bevel gears 46 which mesh with gears 33. At one projecting end thereof the shaft 45 mounts a gear 47 which meshes with pinion 44. A pinion 48 also meshes with gear 47 and is mounted in a stud shaft 49 journaled in one of the standards 36. A gear 50 is mounted on the projecting end of shaft 47 and meshes with pinion 48.

In the operation of the device, the wire 20 is fed to and between a set of the gears 18-19 by which it is crimped in a vertical plane as shown at run 51 thereof. These gears serve to advance the wire. The run 51 passes to and through the slotted bushing 25-26. The narrow width of the slot of this bushing serves to position the run 51 with its crimps in a substantially vertical plane. The wire then passes from the bushing through a passage 24 in the gear block to and between one of the sets 28-31 of the horizontal crimping gears in the gear blocks. The horizontal crimping gears rotate at a slightly greater peripheral speed than the gears 18-19 and tension and reshape the crimped wire. The reshaping tends to twist and bend the wire. The wire is restrained by the slot in bushing 25-26 from rotating to permit the previously formed crimp from meshing with the horizontal crimping gears. The resultant reshaping of the wire tends to reduce the amplitude of the vertical crimp to a narrow or shallow undulation while imparting a major sinuous bend in a horizontal plane to the wire. The reshaped wire then passes in a run 52 through a passage 28 in the gear block to and across the shear plate 35, being so advanced by the crimping gears. The shear blades 39 serve to sever the advancing run 52 at regular intervals.

The severed sections or elements 53 of the wire are illustrated in Figs. 3 and 4. Fig. 3 illustrates the major sinuous bends imparted by the horizontal crimping gears 28-31, and Fig. 4 illustrates the minor undulations in a plane transverse to the major bends thereof which result from the action of the horizontal crimping gears upon the previous vertical crimping of the wire imparted by the vertical gears 18-19. The length of each element 53 is the same by virtue of the equiangular mounting of the shearing blades 39 upon the mounting discs 38 and the timed relation of the rotation of said discs to the various crimping gears effected through the train of driving gears therefor. The size and shape of each of the uniform elements may be varied at will by substituting crimping gears having different configurations and sizes of gear teeth and by substituting rotary cutters having blades of different peripheral spacing. Alternatively, the length of each element 53 may be varied by sub-

stituting gears of a different ratio for the gears 41 and 43.

In the operation of the device, it will be observed that the various crimping gears serve both to shape the wire and to advance the wire. The positioning of the crimps of the wire between the two sets of crimping gears by the bushings so that the second set of gears will produce the desired shape is important in the device. Likewise, uniformity of the bending is insured by this bushing. The proper timing of the operating parts is also important. If desired, the positioning of the blades on the various cutting discs may be staggered for smoother operation without sacrifice of uniformity. The accessibility of the various operating parts, as by removal of upper gear block 23, is important for proper threading of the device and for substitution of operating parts for making different sizes and shapes of packing material. Another important feature of the device is that a minimum number of direct drive connections to the various parts, and particularly the horizontal crimping gears, are required; and at the same time not more than one gear is driven through the wire in any drive sequence. The latter feature minimizes the danger of breakage of the wire. The device also provides adequate guides to permit the wire to be properly directed from its advancing means in a pushed action without danger of such deflection as would detract from the uniformity of the elements 53.

We claim:

1. A wire working device comprising a frame, means for journaling a wire reel on said frame, means for successively crimping a wire sinuously in two different planes, said crimping means serving to advance said wire, means for guiding said wire, and means operating in timed relation to said last acting crimping means for shearing said crimped wire in uniform lengths, said guide means including a narrow guide passage between said crimping means.

2. A wire working device comprising a frame, means for journaling a wire reel on said frame, means for successively crimping a wire sinuously in two different planes, said crimping means serving to advance said wire, and means positioned between said crimping means for positioning the wire crimps produced by the first acting crimping means in a predetermined plane as the wire is advanced to the last acting sinuously crimping means.

3. A wire working device comprising a frame, means for journaling a wire reel on said frame, means for successively crimping a wire sinuously in two different planes, the last acting crimping means serving to advance said wire and operating at a slightly greater peripheral speed than said first acting crimping means, and shearing means operating in timed relation to said last acting crimping means.

4. A wire working device comprising a frame, means for journaling a wire reel on said frame, a toothed wire crimping means journaled transversely of said frame, a second toothed wire crimping means journaled vertically of said frame, and slotted guide means between said first and second crimping means for controlling the position in which wire crimped by said first crimping means advances to said second crimping means.

5. A wire working device comprising a frame, wire feed means carried by said frame, a pair of crimping gears journaled on said frame, a second

pair of crimping gears journaled on said frame on an axis angularly displaced from the axis of and operating at faster speed than said first crimping gears, slotted wire guiding means between said gear pairs and means for shearing wire crimped by said means, said shearing means and said second pair of crimping gears being driven in timed relation and said crimping gears serving to advance said wire to said shearing means.

6. A wire working device comprising a frame, wire feed means carried by said frame, a pair of crimping gears journaled on said frame, a second pair of crimping gears journaled on said frame on an axis angularly displaced from the axis of and operating at faster speed than said first crimping gears, slotted wire guiding means between said gear pairs and means for shearing wire crimped by said means, said shearing means and said second pair of crimping gears being driven in timed relation and said crimping gears serving to advance said wire to said shearing means, and means for guiding said wire from said second crimping gears to said shearing means.

7. A wire working device comprising a frame, wire feed means carried by said frame, a pair of crimping gears journaled on said frame, a second pair of crimping gears journaled on said frame on an axis angularly displaced from the axis of said first crimping gears, and means for shearing wire crimped by said means, said shearing means and said crimping gears being driven in timed relation and said crimping means serving to advance said wire to said shearing means, and a casing enclosing said second crimping gears and having guide passages for said wires including a narrow passage leading to said second gears.

8. A wire working device comprising a frame, wire feed means carried by said frame, a pair of crimping gears journaled on said frame, a second pair of crimping gears journaled on said frame on an axis angularly displaced from the axis of said first crimping gears, and means for shearing wire crimped by said means, said shearing means and said crimping gears being driven in timed relation and said crimping gears serving to advance said wire to said shearing means, and a gear block recessed to receive said second crimping gears, said block having aligned passages for receiving and guiding said wire including a lead-in passage of a width and depth corresponding to the lateral dimensions of wire crimped by said first gears.

9. A wire working device comprising a frame, wire feed means carried by said frame, a pair

of crimping gears journaled on said frame, a second pair of crimping gears journaled on said frame on an axis angularly displaced from the axis of said first crimping gears, and means for shearing wire crimped by said means, said shearing means and said crimping gears being driven in timed relation and said crimping gears serving to advance said wire to said shearing means, a gear block recessed to receive said second crimping gears, said block having aligned passages for guiding said wire to and from said gears, and a bushing in the passage leading to said second gears having a narrow guide slot for positioning the crimps of said wire formed by said first crimping gears.

10. A wire working device comprising a wire feed means, means for sinuously crimping wire in one plane, means for again sinuously crimping said crimped wire in a different plane, means between said crimping means for restraining said crimped wire against rotation, and means operating in timed relation to said last named crimping means for severing said crimped wire in uniform lengths.

11. A wire working device comprising a wire feed means, means for sinuously crimping wire in one plane, means for again sinuously crimping said crimped wire in a different plane, means between said crimping means for restraining said crimped wire against rotation, and means for severing said crimped wire in uniform lengths, and means for operating said second crimping means at a greater peripheral speed than said first crimping means whereby said second crimping means tensions the crimped wire fed thereto and reduces the amplitude of the bend of said wire in said first plane.
